UNITED STATES PATENT OFFICE.

WALTER J. DOODY, OF BOSTON, MASSACHUSETTS.

TESTING DEVICE FOR IGNITION SYSTEMS.

Application filed September 4, 1924. Serial No. 735,788.

This invention relates to a testing device for ignition systems and more particularly to a testing device for the jump spark ignition systems commonly used upon internal 5 combustion engines of motor vehicles.

The object of the invention is to provide a novel and improved device of the character specified, by which the spark coils controlling the ignition leading to any particular 10 cylinder of the engine may be selectively rendered inoperative in a simple and highly convenient manner to the end that the operator may test the ignition circuits of the engine by selectively cutting out successive 15 cylinders of the engine to locate the trouble.

The spark coils controlling the ignition of the usual motor vehicle engine are arranged side by side in a coil box, usually supported upon the dash of the vehicle and with lead 20 wires connecting the terminals of the box with the spark plugs and other portions of the ignition circuits. The circuits are arranged in such manner that one spark coil controls the ignition of a particular cylinder.

25 The spark coils are enclosed within the box by a removable cover and at the present time it is the usual practice, in order to test the ignition system for trouble, to selectively short circuit successive spark coils and for 30 this purpose the operator is required to remove the cover from the box and to hold down the usual vibrators with the fingers. The coil box is usually attached to the dash well under the cowl of the motor vehicle in

35 an inaccessible position, and it is inconvenient for the operator to reach in under the cowl to the coil box and remove the cover and hold down a particular vibrator whose coil it is desired to short circuit. In accord-

40 ance with the present invention, the coil box is provided with mechanism which is capable of operation from the exterior of the coil box and without requiring the removal of the cover, for selectively rendering 45 the spark coils inoperative for testing purposes. In the preferred form of the invention, the cover of the coil box is provided with operating members projecting through openings therein to above the same,

50 and which are operatively connected with insulating members yieldingly held by springs within the coil box and which are adapted to engage the vibrators to hold down the same when the operating members are depressed. In the use of the testing device embodying this invention, the operator

merely reaches under the cowl and presses down any one of the operating members projecting through the cover to short circuit the particular spark coil. 60

These and other features of the invention will be hereinafter described and particularly defined in the claims at the end of this specification. 65

In the drawing illustrating the preferred form of the invention, Fig. 1 is a plan of a coil box embodying the present invention, with a portion of the cover broken away; Fig. 2 is an inverted plan of the cover of the coil box shown in Fig. 1; Fig. 3 is an 70 elevation with a portion in vertical section of the coil box shown in Fig. 1; and Fig. 4 is a detail in perspective to be referred to. 75

Referring to the drawing, 10 represents the usual coil box which is secured to the dash of the motor vehicle, and in the usual construction of motor vehicle is secured underneath the cowl in an inaccessible position. The coil box 10 illustrated in the drawing is of the type employed upon Ford 80 motor vehicles and is provided with a removable cover 12 which is removably secured to the body of the coil box 10 by clasps 13 as shown in Fig. 3. The spark coils 14, only one of which is shown in Fig. 85 3, are arranged side by side within the coil box 10, one for each cylinder, and the usual electrical connections are made from each spark coil to the spark plug of each cylinder and including the commutator and other 90 standard parts of the ignition circuit. 95

In accordance with the present invention, and as illustrated in the drawing, the cover 12 of the coil box is provided with a plurality of openings 16 therein, one arranged over each spark coil and an operating member 20 is arranged to project through said opening into a position above the surface of the cover, being yieldingly maintained in such position by a leaf spring 22 riveted or otherwise secured to the underside of the cover, as shown in Figs. 2 and 3. The operating member 20 has connected to it, an insulating member 24, herein shown as an insulating block provided with a groove 26 in the under surface thereof, forming in effect a yoke which is adapted to straddle the usual vibrators 28 of the spark coil when the operating member is depressed. With this construction the operator may selectively short circuit the spark coils to locate the 100 source of trouble, by simply reaching in 105 un-

der the cowl and over the top of the coil box and depressing the particular operating member or knob 20 corresponding to the cylinder which it is desired to test, and upon depression of the knob or operating member 20 the insulating block 24 engages the vibrators 28 of the spark coil holding them down and short circuiting the particular spark coil to render it inoperative.

10. In the preferred construction the spring 22, insulating block 24, and operating knob 20 are preferably constructed as a unit such as is illustrated in perspective in Fig. 4, and which may be readily attached to existing 15 covers of coil boxes, after providing such cover with the openings 16.

It will be observed that in accordance with the present invention, the ignition circuits of the different cylinders may be tested in 20 a convenient and exceedingly simple manner without necessitating removal of the cover of the coil box or of access in any way to the interior of the coil box.

While the preferred embodiment of the 25 invention has been illustrated and described, it is to be understood that the invention may be embodied in other forms within the scope of the following claims.

Having thus described the invention, what is claimed is:

1. A coil box having therein a plurality of spark coils provided with vibrators, springs attached to the underside of the cover, insulating members carried by the springs for engaging said vibrators when the springs are depressed, and operating members projecting through the cover and connected with the insulating members and springs, for depressing the springs to cause the insulating members to hold down the vibrators for the purpose specified. 30 35 40

2. As a new article of manufacture, a cover for a coil box provided with openings therein, springs attached to the underside of the cover, insulating members carried by the springs adapted to engage the vibrators of the spark coils when the cover is applied to the coil box and the springs are depressed, and operating members connected with said insulating members and springs and projecting through the openings in the cover to be 45 50 accessible from outside the cover for the purpose specified.

In testimony whereof, I have signed my name to this specification.

WALTER J. DOODY.
